UNITED STATES PATENT OFFICE.

JOSEPH PEYSER, OF MOUNT VERNON, NEW YORK, ASSIGNOR, BY MESNE ASSIGNMENTS, TO ACKERMANN MANUFACTURING COMPANY, OF WHEELING, WEST VIRGINIA, A CORPORATION OF WEST VIRGINIA.

HEADING-MACHINE

1,397,651.

Specification of Letters Patent.

Patented Nov. 22, 1921.

Application filed August 21, 1918. Serial No. 250,764.

To all whom it may concern:

Be it known that I, JOSEPH PEYSER, a citizen of the United States, and a resident of Mount Vernon, in the county of Westchester and State of New York, have invented certain new and useful Improvements in Heading-Machines, of which the following is a specification.

The present invention relates generally to a heading machine such as is used in uniting can bodies and covers, and has for its main object such reorganization of the parts as will produce a simple and efficient structure in which the bodies and covers are associated before they are united, and in which the contents of a can body is compressed against the cover that is to be united with that particular can body.

The invention consists of the general arrangement of the parts hereinafter set forth and also of the particular features of construction that enter into that organization.

In the accompanying drawings the invention is disclosed in a concrete and preferred form in which changes of constructions may be made without departing from the scope of the invention.

In these drawings:

Figure 1 is a front elevation of a machine embodying the invention and showing one can body on the heading or seaming plunger while the latter is elevated and another can being transferred from the can body conveyor to the topping or transfer plunger while the latter is in its lowered position.

Fig. 2 is a view looking in the direction of arrow 2 of Fig. 1 with parts removed and in section.

Fig. 3 is a plan view of Fig. 1.

Fig. 4 is a view of the elements shown at the right hand end of Fig. 1, with parts removed, the heading or seaming plunger being lowered and the topping or transfer plunger elevated.

Fig. 5 is a sectional view on line 5—5 of Fig. 1.

Fig. 6 is a sectional plan view of the parts relating to the can body and cover feeding means substantially on line 6—6 of Fig. 5.

Fig. 7 is a sectional view on line 7—7 of Fig. 3.

Fig. 8 is a sectional detail view on line 8—8 of Fig. 3.

Fig. 9 is a diagrammatic view of the action of the can body and cover feeding means. 55

Fig. 10 is a diagrammatic view of the timing of the elevation of the can body on the topping or transfer plunger.

1 indicates a framework of any suitable construction mounting a heading or seaming mechanism 2 that is adjustable by means of a handwheel 3 in a well known manner. The seaming members 4 are of the character commonly known as "double seaming members" and may take such form as is desirable. An approved form, suitable for use in a machine of this character, is shown in application Ser. No. 180,270.

Directly under the seaming head 2 is a seaming plunger 5 and adjacent thereto and in advance thereof, with respect to the direction of movement of the cans through the machine, is a topping or transfer plunger 6. The seaming plunger 5 is carried by a spindle 7 supported by bearings 8 and 9 and actuated from a cam 10 (Fig. 2) by means of a cam lever 11 pivoted at 12 and having a roller 13 engaging said cam 10 and having also a bifurcated member 14 (Fig. 4) that engages spindle 7, in a known manner, to lift 70 and lower plunger 5, the two positions of said plunger being indicated respectively in Figs. 1 and 4. The topping or transfer plunger 6 is carried by a sleeve 15, mounted loosely on spindle 7, and is actuated from a cam 16 by means of a lever 17 pivoted at 18 and having a roller 19 engaging cam 16 and having a bifurcated member 20 that engages sleeve 15 to raise and lower plunger 6, the two positions being indicated respectively in 75 Figs. 4 and 1. It will be observed that cams 10 and 16 act oppositely so that when plunger 5 is up, plunger 6 is down, and vice versa.

It will be seen from Fig. 4 that, when plunger 5 is down and plunger 6 up, the two 80 plungers are on a level with each other so that a can body may be transferred from 6 to 5; and, it will also be seen, from Fig. 1, that when plunger 5 is up, the seaming operation takes place, and that when plunger 6 is 85 down, it is on a level with a raceway 21 so that a can body may be transferred from the raceway to plunger 6. The can bodies are moved over raceway 21 in timed relation by projections 22 of a chain 23, said can body 90 sliding on the raceway and the chain moving

100

105

110

115

120

125

130

135

in a groove 24 and actuated by means of sprockets 25 and 26. Plunger 6 has a central aperture 27 (best seen in Fig. 6) in line with which sprocket 25 is located and admits of passage therethrough of projections 22 and chain 23, as will presently appear. Cams 10 and 16 are mounted on an upright cam shaft 28 that derives its motion from a power shaft 29 by means of a worm 30 and worm gear 31.

Mounted on the framework 1 is a bracket 32 and carried by the latter, and extending beneath the seaming mechanism 2, is a plate 33 that has an opening 34 in line with the seaming members and an opening 35 in line with a cover magazine 36. The opening 34 is large enough to admit of the passage of a cover therethrough as well before as after seaming. The cover magazine 36 is located above the path of the can bodies and in advance, with respect to the direction of movement of the can bodies through the machine, of the topping or transfer plunger 6 and in a straight line with it.

A guideway for the covers from magazine 36 to the seaming head is provided by the following means. Carried on the underside of the plate 33 (Figs. 5 and 6) are a plurality of ledge members 37, 38, 39, 40 and 41. The members 37 and 38 are directly beneath the cover magazine 36 and, in effect, constitute a part of it since the lowermost cover 42 rests on them. It will be observed, however, that while these ledge members limit downward movement of the cover stack, they admit of lengthwise movement of the lowermost cover out of the plane of the magazine,—that is, covers may be moved to the right in Fig. 6. The ledge member 39 is located adjacent one side of the topping plunger 6; and adjacent the other side of said plunger is a cover detector consisting of a lever 43 mounted on a rockshaft 44 and forming part of the guideway for the cover and to this end, having a ledge 45, as shown. The members 40 and 41 are located adjacent to seaming plunger 5 but, as will presently appear, these members may be dispensed with. The cover magazine 36 consists here of a hopper 46 and four upright posts 47.

The cover detector 43 is normally held in the position shown in Fig. 6 by the passing covers and, when so held, maintains rockshaft 44 in such position that the fast clutch member 48 (Fig. 5) will be in engagement with the loose clutch member 49. This is done through the instrumentality of a lever 50 (Fig. 1) and a link 51 (Fig. 5) connected to a bell crank 52 provided with a bifurcated portion 53 that engages the fast clutch member 48. If a cover is absent, a spring 54 acts upon bell crank 52 to separate the clutch members 48 and 49. The sprocket 25 that drives the can chain 23 is carried by a stud shaft 55, on one end of which is a

bevel gear 56 meshing with a bevel gear 57 on the loose clutch member 49. It will therefore be understood that as long as covers are passing and hold detector 43 in proper position, clutch members 48 and 49 will be in engagement and can body chain 23 will continue to feed a can body at regular intervals but that when a cover is missing, the can body feed will cease.

The feeding of the covers is controlled by the passage of the can bodies in the following manner: A can body detector 58 (Figs. 1 and 6) is mounted on an arm 59 carried by a rockshaft 60. Mounted on this rockshaft is an arm 61 (Figs. 3, 6 and 5) that is provided at its outer end with a stud 62 engaging a separating knife 63. The stud passes through a slot 64 in a cam slide 65, and knife 63 moves in guides 66 and passes through plate 33 into the cover magazine at a point just above the ledge member 37. The cam slide 65 has a roller 67 that engages in a cam 68. The detector 58 projects slightly into the path of the can bodies, and, whenever a can body passes, said detector is moved outwardly to an extent sufficient to cause rockshaft 60 to actuate arm 61 and thereby cause the latter to withdraw knife 63 from the cover magazine so that a cover will drop in position on ledges 37 and 38. Rotation of the cam 68 will thereafter actuate cam slide 65 which, in turn, will engage stud 62 and thereby move knife 63 and cause the latter to enter the cover magazine between the lowermost cover and the one next adjacent. Other means, to be presently described, then removes the lowermost cover from the magazine. In case no can body passes, it is evident that rockshaft 60 is not actuated and that knife 63 is not withdrawn from the stack; and, that consequently, no cover will drop on ledge 37. The action of cam 68 is, under these circumstances idle because, when cam slide 65 is actuated, stud 62, on account of its position and the presence of slot 64, will not be moved.

69 indicates a double mold for shifting the can body and cover. This mold consists of a plurality of pockets,—here two, 70 and 71,—mounted on a carrying member 72. 73 and 74 are two gears rotating in the same direction and receiving motion from gear 75 on cam shaft 28. Gears 73 and 74 carry crank pins 76 and 77 which are provided with shoes 78 that slide in slots 79 and 80 of the carrying member 72. 81 is a guide or cam slot in bracket 32 into which extends a roller 82 mounted on the carrying member. The pocket 70 is provided with ledges 83 (Figs. 4, 5 and 6) that engage the lowermost cover in the cover magazine and, moving it off the ledges 37 and 38, slide it into position on ledges 39 and 45. The pocket 71 takes the can body with a cover in position

and moves it from plunger 6 onto plunger 5 removing, at the same time, a can from plunger 5 out of the machine.

84 is a rotatable dial (Figs. 3, 7 and 8) 5 that receives motion by means of bevel gears 85 and 86 from a shaft 87 carrying the sprocket 26 of the can body chain. Arranged above this dial is an outer stationary 10 guide wall 88 that terminates in the straight guide 89 adjacent one side of can body chain 23 and an inner stationary guide wall 90 that terminates in a straight guide 91 adjacent the other side of the can body chain. It will be noted that the dial is closely adjacent 15 the can body raceway 21, and that the latter is cut away at one point 92 to permit the dial to bring the can bodies into line with projections 22 of the can body chain. Adjacent the dial is also a conveyer 93 for 20 feeding can bodies from a suitable source, such as a filling machine, to the dial. The outer periphery of the dial is provided with a plurality of notches 94 spaced apart a distance equal to the diameter of a can body, or 25 substantially so. Pivotaly supported adjacent each notch is a counterweighted projection 95 that normally projects above the surface of the dial. Located beneath the dial is a stationary cam 96 that engages with 30 each projection 95 as it arrives at the point where conveyer 93 is located, thereby depressing said projection. If a can body comes over one of the notches 94, the projection 95 will remain in its depressed position 35 after it leaves cam 96 but when other can bodies coming from conveyer 93, have crowded the first can body a given distance, projection 95 will rise through its notch and act as a spacing member between can bodies 40 and will thereafter advance the can body between walls 88 and 90 until it reaches can body chain 23.

The operation of the machine is as follows: The can bodies are delivered in the 45 manner described by conveyer 93 to dial 84 and thence to raceway 21 where a can body is then advanced by the can body chain in timed relation until it arrives adjacent plunger 6. At this moment, said plunger is in 50 its lowermost position which is on a level with raceway 21. As projection 22 continues to push the can body, the latter will gradually be seated on plunger 6 and, when it has moved over on said plunger a given distance, 55 the plunger rises, projection 22 meanwhile continuing to push the can body until it is in proper position on said plunger. Meanwhile, a cover has been moved by ledges 83 of pocket 70 from ledges 37 and 38 to the 60 ledges 39 and 45 and will be in position in line with the can body being raised by the plunger 6. The result is that the contents of the can body is crowded down by the cover as the can body presses the latter 65 against plate 38. The pocket 71 now grasps

the can body and moves it from plunger 6 to plunger 5 which latter, at this moment, is in its lowermost position so that the two plungers are on the same level. The movement of the can body carries the cover with 70 it which is brought from the ledges 39 and 45 onto the ledges 40 and 41. The ledges 40 and 41 are not necessary, but may be used if desired, as the cover is in position and has partly entered the mouth of the can body 75 before the latter is moved. Plunger 5 now rises and the seaming operation takes place, after which plunger 5 descends. It will be understood that while the can body and cover are being moved from plunger 6 to 80 plunger 5, another cover is being moved from the cover magazine to ledges 39 and 45 and that while the seaming operation takes place another can body is being moved from raceway 21 to plunger 5. If a can body is 85 missing, detector 58 prevents the feeding of a cover, and if a cover is missing, detector 43 stops the feeding of can bodies by uncoupling clutch members 48 and 49 and thereby stopping the movement of chain 23. 90 It will also be observed that when chain 23 ceases to move, sprocket 26 also stops and therefore dial 84 is no longer rotated.

The action of the double mold 69 is peculiar. Considering the position shown in 95 Fig. 6 as denoting the beginning and the end of a cycle of movements of the carrying member 72, the direction of rotation being as indicated by the arrows, then during the first 90° of the crank movement, carrying 100 member 72 will move in a curved path away from the can body and cover. During the next 90°, shoes 78 of said cranks will traverse slots 79 and 80 and the carrying member 72 will move to the left in a straight line, 105 roller 82 acting against the straight surface 99 of cam guide 81. The parts will now occupy the position shown in Fig. 9. During the third quarter of a revolution, the member 72 moves toward the cover and can 110 body in a curved path and during the remaining 90°, member 72 will move in a straight path to the right on account of surface 102. When the cranks have rotated about 224°, the left hand ledge 83 of pocket 115 70 strikes the cover held on ledges 37 and 38 and, at about the same time, the left hand horn of pocket 71 strikes the can body on plunger 6 as it is being moved by projection 22 of the can body chain. At this moment, 120 the carrying member is moving to the right at substantially the same speed as that of chain 23. From this point on, however, member 72, due to the crank movement, gains in speed and the speed of the can body is 125 therefore accelerated to such extent that the can body will be moved away from projection 22 and permit the latter to descend through aperture 27 in plunger 6. The acceleration of the movement of the can body 130

continues until the cranks have rotated 270° when the movement is decelerated until the can body reaches, as it does at 360° , its proper position on seaming plunger 5. At that time, the can body is practically at a standstill and pocket 71 now disengages the can body. This action is plotted on the line z of Fig. 9 where it will be seen that the can body advances, while under the influence of can body chain 23, equal distances in equal periods of time and that, when it reaches the position indicated by 224° , pocket 71 becomes effective and accelerates, and then decelerates, the movement of the can body as indicated by the unequal spacing between 224° and 360° on line z . The advantage of this resides in the fact that the can body is moved gently so that its contents are not spilled. It will be further understood that while the can body is being moved onto plunger 6 by means of chain 23, said plunger will rise. The relation between these movements is shown in Fig. 10 where it is seen that while the center line y of the can body moves from 140° to 224° , as measured by the rotation of the cranks, the plunger rises, as indicated by the levels z of Fig. 10, so that at 224° plunger 6 is completely elevated and the can body is in alinement with the cover that is held by ledges 39 and 45.

The movement of the can body under the influence of the mold is duplicated in the movement of the cover from ledges 37 and 38 to ledges 39 and 45. The cover is first moved slowly and then more quickly and is then gradually slowed down to a state of rest. It will be understood that in this manner, the cover reaches its position in line with the topping plunger 6 before the can body that is being moved by the chain is centered on said plunger.

The chief advantages of this machine are that the structure is compact; the handling of can bodies and covers simple and reliable; the topping of the contents of the can body is effected just prior to seaming so that there is not sufficient time for it to work out again; and the topping of the contents is effected, not by an independent member, but by the cover of the can body.

I claim:

1. In a heading machine, two adjacent plungers, one of which has an aperture, an upright member carrying one of said plungers, a sleeve surrounding said member carrying the other of said plungers, means for actuating the member and the sleeve independently one of the other, a rotatable member located in the plane of the aperture, a conveyer passing around said rotatable member for carrying can bodies to the plunger having the aperture, and means for conveying can bodies from said last-mentioned plunger to the other plunger.

2. In a machine of the character set forth:

two closely adjacent plungers each having an up and down movement and the surfaces of which are at the same level when one plunger is in its upper position and the other is in its lower position, and means for transferring a can body directly from one plunger to the other when they are at the same level.

3. In a machine of the character set forth: two closely adjacent plungers each having an up and down movement and the surfaces of which are at the same level when one plunger is in its upper position and the other is in its lower position, means for transferring a can body and a can cover directly from one plunger to the other when they are at the same level, means for associating the can body and the cover on the first plunger, and means for uniting the can body and the cover when they have been transferred to the second plunger.

4. A heading machine comprising: heading mechanism, a heading plunger in line therewith, means for lifting and lowering the heading plunger into and out of operative relation with respect to the heading mechanism, and a can body feeding conveyer the upper surface of which is below the level of the lower position of the heading plunger, a transfer plunger intermediate the conveyer and heading plunger for receiving a can body from the conveyer and delivering it to the heading plunger and having an up and down movement from the level of the upper surface of the conveyer to the level of the heading plunger when the latter is in its lower position, means for actuating said transfer plunger, and means for moving the can body from the transfer plunger to the heading plunger.

5. A heading machine comprising: heading mechanism, a heading plunger in line therewith, means for lifting and lowering the heading plunger into and out of operative relation with respect to the heading mechanism, a can body feeding conveyer the upper surface of which is below the level of the lower position of the heading plunger, a topping plunger, intermediate the conveyer and heading plunger for receiving a can body from the conveyer and delivering it to the heading plunger and having an up and down movement from the level of the upper surface of the conveyer to the lower level of the heading plunger, means for feeding a cover in position above the topping plunger, means for actuating said topping plunger to compress the contents of the can body against the can cover, and means for moving the can body and cover from the topping plunger to the heading plunger.

6. A heading machine comprising: a cover magazine open at the bottom, means normally operative for separating the lower-

- most cover from the stack, means for feeding can bodies under the cover magazine, means for withdrawing said separating means from the stack rendered operative by 5 the passage of a can body, a guideway extending from said magazine and comprising a series of ledges for the support of a cover, means actuated by one of said ledges for rendering the can body feeding means 10 inoperative when a cover is missing, and means for uniting the can body and cover.
7. A heading machine comprising: a cover magazine open at the bottom, means normally operative for separating the lowermost cover from the stack, means for feeding can bodies under the cover magazine, means for withdrawing said separating means from the stack rendered operative by 15 the passage of a can body, a guideway extending from said magazine and comprising a series of ledges for the support of a cover, means actuated by one of said ledges for rendering the can body feeding means 20 inoperative when a cover is missing, means for associating the can body and cover before they reach the position where they are united, and means for transferring the can body, and thereby the cover, from the point where they are associated to the point where 25 they are united.
8. A heading machine comprising: a cover magazine, heading mechanism, a plate below the magazine and heading mechanism, said plate having an opening in line with 30 the magazine and an opening, large enough to admit of the passage therethrough of a can body and cover as well before as after heading, in line with the heading mechanism, means for feeding a can body into 35 alignment with the heading mechanism, a guideway adjacent the underside of the plate extending from one opening to the other, means for feeding a cover from said cover magazine through said guideway, a 40 detector forming a part of said guideway for rendering the can body feeding means 45 inoperative when a cover is absent, and means for raising the can body and cover through the opening in the plate into operative relation with the heading mechanism. 50
9. A heading machine comprising: a heading mechanism, a cover magazine located in advance of the heading mechanism, a can body raceway below the magazine, a guideway for the covers above the raceway and 55 below the magazine, means for moving the can bodies through the raceway, means for separating the lowermost cover from the stack in the magazine, means for feeding the 60 covers from said magazine through said guideway, a detector adjacent to the can body raceway controlling the cover separating means, and a detector forming a part of the cover guide controlling the can body 65 moving means.
10. A heading plunger, a transfer plunger in advance of the heading plunger, a conveyer for moving can bodies in spaced relation to said transfer plunger, a cover magazine in advance of the transfer plunger, 70 a cover guide above the path of the conveyer, a carrying member having two pockets one for the cover and one for the can body, and means for moving said carrying member in a straight path to shift a can body from the transfer plunger to the heading plunger and to feed the cover from the magazine through the cover path, said means including devices for first accelerating and then decelerating the movement of the carrying member. 75
11. A heading plunger, means for lifting and lowering said plunger, a topping plunger, means for lifting and lowering said topping plunger in alternation with the heading plunger, said plungers being at the same level when the heading plunger is in a lower position and the topping plunger is in an upper position, a can body conveyer for feeding cans in spaced relation to said 80 topping plunger when it is in a lower position and while it is being elevated, a carrying member, and means for moving said carrying member in a straight path to shift the can body from the topping plunger to the heading plunger, said means including devices for first accelerating and then decelerating the movement of the carrying member. 85
12. A heading plunger, means for lifting and lowering said plunger, a topping plunger, means for lifting and lowering said topping plunger in alternation with the heading plunger, said plungers being at the same level when the heading plunger is in a lower position and the topping plunger is in an upper position, a can body conveyer for feeding cans in spaced relation to said 90 topping plunger when it is in a lower position and while it is being elevated, a carrying member, and means for moving said carrying member in a straight path to shift the can body from the topping plunger to the heading plunger, said means including devices for first accelerating and then decelerating the movement of the carrying member. 95
13. A plunger having an aperture in its surface, a can body conveyer having projections for advancing can bodies in spaced relation to said plunger, a rotatable member in line with the aperture aforesaid over which the conveyer passes, means for lifting the plunger while the can body is moving from the conveyer to the plunger, and means for re- 100
- 110
- 115
- 120
- 125
- 130

moving the can body from the plunger with an accelerated motion to give clearance sufficient to admit of the passage of a projection on the conveyer down through the aperture 5 of the plunger.

14. A plunger having an aperture in its surface, a can body conveyer having projections for advancing can bodies in spaced relation to said plunger, a rotatable member 10 in line with the aperture aforesaid over which the conveyer passes, means for lifting the plunger while the can body is moving from the conveyer to the plunger, and means for removing the can body from the plunger 15 with an accelerated motion to give clearance sufficient to admit of the passage of a projection on the conveyer down through the aperture of the plunger and to then move said can body with a decelerated motion, and 20 a heading plunger for receiving the can body from the first plunger.

15. Means for shifting a can part comprising: a carrying member, means for moving said carrying member in a continuous orbit 25 toward and away from the can part and in a straight line while shifting the can part consisting of rotating means including a crank element, slidably connected with the carrying member, and a stationary member for directing the movement of the carrying member, said crank element being so disposed that when the carrying member is moving in a straight path while engaging the can part, it is traveling first with a gaining 30 movement and then with a lagging movement.

16. A heading machine comprising: a heading mechanism, a heading plunger, a transfer plunger, a can body conveyer for 40 feeding a can to the transfer plunger, means for shifting the can body from the transfer plunger to said heading plunger, an upright shaft, cams and connections from said shaft for lifting and lowering the plungers, means

for driving the can body conveyer from said shaft, means for moving the shifting means from said shaft, a cover magazine, means actuated from said upright shaft for feeding covers from said magazine, and a cover detector controlling the driving means of the 50 can body conveyer.

17. A heading machine comprising: a heading mechanism, a heading plunger, a transfer plunger, a can body conveyer for feeding a can to the transfer plunger, means 55 for shifting the can body from the transfer plunger to said heading plunger, an upright shaft, cams and connections from said shaft for lifting and lowering the plungers, means for driving the can body conveyer from said shaft, means for moving the shifting means 60 from said shaft, a cover magazine, means actuated from said upright shaft for feeding covers from said magazine, a cover detector controlling the driving means of 65 the can body conveyer, and a can body detector controlling the feeding of covers.

18. A heading machine comprising: a heading mechanism, a heading plunger, a transfer plunger, a can body conveyer for 70 feeding a can to the transfer plunger, means for shifting the can body from the transfer plunger to said heading plunger, an upright shaft, cams and connections from said shaft for lifting and lowering the plungers, means 75 for driving the can body conveyer from said shaft, means for moving the shifting means from said shaft, a cover magazine, means actuated from said upright shaft for feeding covers from said magazine, a cover detector 80 controlling the driving means of the can body conveyer, and a dial for feeding can bodies to the conveyer driven from the latter.

Signed at New York, in the county of 85 New York and State of New York, this 16th day of August, 1918.

JOSEPH PEYSER.
